UNITED STATES PATENT OFFICE.

JOHN E. GRAF, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

AUTOMATIC MUSICAL INSTRUMENT.

Application filed June 30, 1923. Serial No. 648,891.

This invention relates to improvements in automatic musical instruments.

It has for its chief object to provide improved means for automatically reversing 5 the roll-driving mechanism upon the completion of the playing of the music-sheet.

Another object of the invention is to provide automatic means for restoring the roll-driving mechanism to playing position upon 10 the completion of the rewinding of the music-sheet.

A further object is the provision of manually-controlled means for stopping the playing of the instrument at will.

15 A still further object of the invention is to provide an automatically-operated instrument of this character which is reliable and efficient in operation and which is provided with no delicate parts liable to get out of 20 order or out of adjustment.

In the accompanying drawings:

Figure 1 is a front elevation, partly in section, of a tracker-box and roll-driving mechanism embodying my improvements, 25 the parts being shown in their playing position. Figure 2 is a horizontal section on line 2—2, Fig. 1. Figure 3 is a fragmentary rear view, partly in section, of the roll-reversing mechanism, showing the parts in 30 their playing position. Figure 4 is a similar view, showing the parts in position for rewinding the music sheet. Figure 5 is a transverse vertical section on line 5—5, Fig. 2. Figure 6 is an enlarged sectional detail 35 view, partly in perspective, of the actuating pneumatic and the pallet valve assembly. Figure 7 is a transverse vertical section of the pneumatic in the plane of line 7—7, Fig. 6, together with detailed sectional perspective views of the rewind cut-off block 40 assembly, the rewind cut-off slide assembly, and the tracker board and note sheet connected therewith. Figure 8 is a horizontal section on line 8—8, Fig. 7. Figure 9 is an 45 enlarged transverse section on line 9—9, Fig. 2.

Similar characters of reference indicate corresponding parts throughout the several views.

50 In its general organization, the device comprises the usual roll frame including the tracker board, music roll and take-up roll, transmission mechanism for said rolls, an oscillating driving shaft shiftable into and

out of operative engagement with said transmission mechanisms, respectively, a clutch and a reverse lever therefor associated with one of the transmission mechanisms, a rewind action assembly or pneumatic, a flexible connection between the latter, said reverse lever and said driving shaft, the pneumatic being automatically actuated in one direction to effect the rewinding of the music sheet when the selection is completed, automatic means for effecting the actuation of the pneumatic in the opposite direction or to playing position upon the completion of the rewinding of the music-sheet, and manually-controlled means for reversing and stopping the instrument at will.

In the drawings, A indicates a wind chest of any suitable and well-known construction, and B a pump or main suction bellows operated in the usual manner.

Mounted in the usual frame 10 is the 75 tracker board 11, the music roll 12 and the take-up roll 13, the numeral 14 indicating the perforated music-sheet. The right hand ends of the roll-spindles are engaged with the customary clutch-members or heads 15, 16, secured to the take-up and rewind shafts 17, 18, respectively, which are journaled in the adjacent side wall of said frame. The rewind shaft 18 is provided with a spur gear 19 which meshes with a similar gear 20 secured to a countershaft 21 having a driven member or friction disk 22 at its outer end. Loosely mounted on the take-up shaft 17 and held against longitudinal movement thereon is a gear 23 which is in constant 80 mesh with a pinion 24 fixed on a horizontal shaft 25 supported by a bracket 26 secured to the adjacent wall of the roll-frame. At its outer end said horizontal shaft carries a driven member or friction disk 27. A 85 grooved clutch collar 28 is splined on the outer end of the rewind shaft and carries clutch pins 29 adapted to engage similar pins 30 projecting from the hub of the gear 23. Connected to this clutch collar is a vertically-swinging shifting lever 31 fulcrumed at its upper end, as shown at 32, to the bracket 26.

33 indicates a substantially upright driving shaft facing the friction disks 22, 27 and carrying friction wheels 34, 35 adapted to engage said disks, respectively. This shaft is journaled intermediate its ends in

an oscillating frame 36 pivoted at 37 to the outer end of a suitable bracket 38 projecting from the roll-frame 10. The fulcrum 37 of this oscillating frame is arranged transversely of the friction disks and is located in a plane between the shafts of the latter, so that when the shaft 33 is rocked in one direction the upper friction-wheel 34 engages the companion friction disk 22 and the lower friction wheel 35 clears the corresponding friction disk 27, while when said shaft is rocked in the opposite direction, the position of said wheels is reversed. The constant rotation of the driving shaft 33 in the same direction thus causes the music-sheet to be taken up or rewound according as said shaft is rocked, in one or the other direction. Said shaft may be driven from a countershaft 39 through the medium of bevel gears 40, 41, the countershaft being driven by an electric motor or other means, not shown.

At its lower end the shaft 33 is provided with a coupling head or block 42 connected by oppositely-extending links 43, 44 to the lower end of the shifting lever 31 and to the movable board 45 of a rewind pneumatic 46, respectively. That end of the link 43 which is connected to the shifting lever is provided with a longitudinal slot 47 in which its pivot pin 48 is free to move, thus permitting said lever to be moved manually sufficiently to disengage the clutch collar 28 from the gear 23 without changing the position of the shaft 33 or the pneumatic 46. This manual movement of the shifting lever is effected by a horizontal slide bar 49 provided at one end with a knob or handle 50 and at its other end with an opening 51 into which the lower end of a vertically-swinging rock lever 52 projects. Said rock lever is fulcrumed intermediate its ends on a bracket 53 secured to the right hand wall of the roll-frame 10, its upper arm being adapted to bear at its outer edge against the opposing inner side of the pivot pin 48, as clearly shown in Fig. 3. Thus, when the device is in its playing position shown in Figs. 1, 2 and 3, and it is desired to stop the rolls 12, 13 to arrest the travel of the music sheet, the slide bar 49 is pulled outwardly far enough to cause the rock lever 52 to move the shifting lever 31 a sufficient amount to release the clutch collar 29 from engagement with the gear 23, as shown by dotted lines in Fig. 3, the shaft 33 and rewind pneumatic being unaffected and remaining in their operative playing position. In this position of the parts the music and take-up rolls can be turned by hand independently of the driving and rewind mechanism, for tuning purposes, and the music roll can be replaced by another without stopping the motor.

A coil spring 54 tends constantly to hold the driving shaft 33 in its normally opera-

tive playing position, while a similar spring 55 applied to the shifting lever 31 tends to hold the clutch collar 28 in engagement with the gear 23.

When the shaft 33 is in position for playing with its friction wheel 35 in contact with the friction disk 27 of the take-up mechanism, the pneumatic 46 is in its inflated or expanded position, shown in Figs. 1, 2 and 3. It is the primary function of this pneumatic to automatically shift said shaft 33 to its reverse position, shown in Fig. 4, after the completion of the last selection on the music sheet. This reverse movement of the shaft releases the clutch collar from engagement with the gear 23, withdraws the lower friction wheel 35 from its companion friction disk 27, and brings the upper friction wheel 34 into engagement with the companion disk 22, whereby motion is transmitted to the music-roll shaft 18 to rewind the music sheet. The automatic means, whereby this reversal of the parts to their rewind position is accomplished, are preferably constructed as follows:

Near one end thereof, the tracker board 11 is provided with a rewind hole 56 with which a corresponding perforation at the end of the music sheet is adapted to register when the playing of the roll is completed. This hole is connected by a tube 57 with a duct 58 in the stationary board 59 of the pneumatic. Mounted on this stationary board, preferably at its lower end, are upper and lower unit valve-blocks 60, 61, of well known construction, each containing a lower pouch or suction chamber 62, an upper valve chamber 63 communicating with the atmosphere through a flushing port 64, a vacuum port 65 connecting said chambers with each other, and a duplex-valve 66 located in the upper valve chamber which cooperates with said vacuum and vent ports. In the bottom of the lower chamber 62 is the customary valve operating pouch 67 and opening into such chamber beneath the latter is an inlet passage 68 adapted for communication with the atmosphere, as will hereinafter appear. The valve chamber 63 of the lower valve block 61 communicates with the interior of the pneumatic 46 through a flushing port 69 while the corresponding valve chamber of the upper valve block 60 is adapted to communicate with the atmosphere through an upright channel 70 in the stationary board 59 of the pneumatic; a lower horizontal port 71 leading therefrom to a pouch chamber 72 formed in a valve block 73 secured to the outer side of said board, and an upper port 74 leading from said pouch-chamber to the duct 58, which, as before stated, communicates with the rewind hole 56 of the tracker board. A valve diaphragm 75 is arranged over the ports 71, 74, as shown in Figs. 6

and 8, and a port 76 in the valve-block 73 communicates at one end with the interior of the pneumatic through a passage 77, while its other end leads to the pouch chamber 72 in rear of said pouch valve. The suction chambers 62 of the upper and lower valve blocks 60, 61 are connected by a manifold passage 78 with the suction bellows B of the instrument. As shown in Fig. 7, this manifold passage is connected by a tube 79 with a suction controlling or cut off valve block 80 communicating with the suction bellows by a trunk 81. This valve block contains ports 82, 83 controlled by a slide valve 84 having a rod 85 connected to a lateral extension 86 of the slide bar 49, as shown in Figs. 2 and 3, said ports being in communication when the instrument is playing and during the automatic rewinding operation of the music sheet to furnish the necessary suction to the pneumatic 46 and associated parts. When the rewinding operation is effected manually through the shifting of the slide bar 49, the slide valve 84 is moved to its closed position to cut off suction to the rewind pneumatic.

The air inlet passage 68, which opens into the pouch chamber 62 of the lower unit valve block 61, is connected by a tube 87 with the duct 58 in the stationary board of the pneumatic. When the rewind perforation in the music sheet 14 uncovers the hole 56 in the tracker board, atmosphere is admitted thereto and to the pouch chamber of the valve block 61 through the medium of the tube 57, duct 58 and tube 87, whereupon the corresponding duplex valve 66 is raised and the pneumatic 46 is exhausted or collapsed to move the shaft 33 to its reverse position and shift the lever 31 to release the clutch collar 28 from the gear 23, thus rewinding the music sheet. When the pneumatic is exhausted, the pouch chamber 72 of the valve block 73 is likewise exhausted through the port 76 and passage 77, thereby raising the pouch valve 75 and establishing communication between the ports 71, 74, as shown by dotted lines in Figs. 6 and 8. Said lower duplex valve is retained in its raised position to keep the pneumatic collapsed during the rewinding of the music sheet by atmosphere admitted through the port 64 of the upper valve block 60, the duplex valve of the latter being in its lowered position at this time. From the port 64, the atmosphere passes through the channel 70, ports 71, 74, duct 58 and tube 87 to the port 68 of the lower valve block 61, the latter thus acting in the capacity of a retaining valve for holding the pneumatic collapsed, while the upper valve 60 functions as a releasing valve to again permit the expansion of the pneumatic at the end of the rewind operation.

In order to silence the instrument during the rewinding operation, means are provided for cutting off the suction to the wind chest simultaneously with the act of collapsing the pneumatic 46. In the example shown in the drawings, particularly Figs. 1, 2, 3, 4 and 7, a controlling valve block 88 is provided having a vacuum port 89 and an air inlet port 90 including a branch 91 which is adapted to communicate with the atmosphere through a channel 92 located between said vacuum and inlet ports, as shown in Figs. 7 and 9. The vacuum port 89 is connected by a tube 93 with a horizontal passage 94 in the stationary board 59 of the rewind pneumatic 46 which communicates with the suction chamber 62 of the lower unit valve block 61 through the port 69. A diaphragm valve or pouch 95 is arranged in the channel 92 between the opposing ends of the vacuum port and the branch port 91 for controlling the admission of atmosphere to the latter, this valve being held down by atmospheric pressure admitted through the port 64 of the lower valve block 61 to keep the branch port closed while the instrument is playing. The inlet port 90 is also connected by a tube 96 with a suction cut-off pouch block 97 to which is connected the trunk 98 leading from the suction bellows B and the trunk 99 leading to the wind chest A. These trunks open into a pouch chamber 100 and communication between them is controlled by a pouch valve 101 arranged opposite the mouth of the trunk 99 which extends into said chamber, the tube 96 leading to the outer side of the pouch valve, as shown at the left in Fig. 1. Thus, when the pneumatic 46 is collapsed and the duplex valve 66 of the lower unit block 61 is raised to establish communication between the suction chamber 62 thereof and the vacuum port 89, suction lifts the diaphragm valve 95 off the branch port 91, whereupon atmosphere is admitted thereto through the channel 92 and thence to the tube 96, causing the pouch valve 101 to move from the full line position to the dotted line position shown in Fig. 1, and cutting off the suction supply to the wind chest.

The air inlet port 90 of the valve block 88 preferably extends from one side thereof to the other and that end of the port opposite the end to which the tube 96 is connected is normally closed by a valve 102 in the form of a flat spring suitably fastened to the corresponding side of the valve block, as shown in Fig. 2. This spring valve functions to control the admission of atmosphere to the inlet port 90 when the rewinding operation is accomplished manually, and to this end projects rearwardly into the path of the lower arm of the rock lever 52 so as to be opened thereby whenever the latter is rocked by a pull on the slide bar 49 to simultaneously shift the clutch lever 31 to its released position.

tion and the slide valve 84 to its closed position. Thus, when the spring valve 102 is opened, atmosphere enters its port 90 and closes the pouch valve 101 to cut off suction 5 to the windchest and silence the instrument, exactly in the same manner as the automatic control is effected.

The means for automatically restoring the parts of the instrument to playing position 10 after the completion of the rewinding operation are preferably constructed as follows:

Co-operating with the take-up roll 13 is a vertically-swinging pawl or finger 103 pivoted at its front end to an arm 104 formed 15 on a rocking sleeve 105 mounted on a horizontal rod 106 parallel with said roll and supported at its ends in the roll-frame 10, as shown in Figs. 1 and 2. This pawl bears on the convolutions of the music sheet opposite 20 a transverse groove or recess 107 in the periphery of the take-up roll, the pawl resting on the latter by its own weight and being adapted to engage the abrupt forwardly-facing shoulder 108 of the recess as soon 25 as the latter is uncovered by the complete unwinding of the music sheet and thus rock the sleeve 105 in a direction away from the roll. Actuated by the rocking action of said sleeve is a pallet-valve 109 fulcrumed at 110 to a valve-block 111 containing an air inlet port 112 controlled by said valve. A connecting rod 113 is joined at one end to a crank arm 114 on the sleeve 105 while its other end engages a fork 115 in the upper 30 end of the pallet valve and passes freely through an opening 116 in the extension 117 of the valve-block. Applied to the end of this connecting rod is a stop or collar 118 for limiting the opening movement of the 35 pallet valve and between the opposing faces of the latter and said extension 117, the rod has an abutment collar 119 which engages the valve and forces it open whenever the 40 rod is pulled forwardly, as by the force exerted by the take-up roll against the pawl 45 103. A coil spring 120 applied to a screw 121 and interposed between the head thereof and the outer side of the pallet-valve tends 50 constantly to hold the latter in its closed position shown in Figs. 5 and 6. The 55 valved-port 112 is connected by a tube 122 with the air inlet 68 leading beneath the valve-operating pouch 67 of the upper unit valve block 60, as shown in Fig. 6. As soon as the recess 107 is uncovered by the 60 complete unwinding of the music sheet, the pawl 103 drops into interlocking engagement therewith, the rotation of the roll causing the pawl to rock in the proper direction to effect the opening of the pallet-valve 109, thus admitting atmosphere to the inlet 68 of said upper valve-block 60 which lifts the pouch 67 to raise the corresponding duplex-valve 66, closing the air inlet port 64 and

opening the vacuum port 65 to connect the 65 channel 70 with the suction chamber 62, thereby closing the pouch valve 75 and causing the pouch 67 and the duplex-valve 66 of the lower valve-block 61 to drop by gravity, cutting off the suction to the pneumatic 46, 70 whereupon the latter is expanded by the spring 54 and the driving mechanism is shifted to playing position. Simultaneously with this action, atmosphere is likewise admitted through the inlet port 64 of the lower unit 75 valve block 60 to the port 69, passage 94 and tube 93 leading to the valve block 88 to restore the diaphragm valve 95 to its original closed position, thereby closing the port 91 to the atmosphere and allowing the pouch valve 101 of the suction cut-off block 97 to open and establish communication between the suction bellows and the wind chest to allow the instrument to play.

The operation of the instrument is as follows:

When the player mechanism is in the playing position shown in Figs. 1, 2, 3, 6 and 7, the rewind pneumatic 46 is expanded or inflated, the clutch collar 28 is in engagement 90 with the take-up roll gear 23, the lower friction wheel 35 is in driving contact with the friction disk 27 so as to impart motion to the take-up roll, these parts being normally retained in this position by the springs 54 and 95 55. At this time the slide-bar 49 is in its innermost position, the duplex valves 66 of the upper and lower unit valve blocks 60, 61 are in their lowered positions, the valve dia- 100 phragms 75 of the valve block 73 is closed, the slide valve 84 of the valve block 80 is open, the diaphragm valve 95 and the spring valve 102 of the valve block 88 are closed, the pouch valve 101 of the suction cut-off block 97 is open and the pallet valve 109 of the valve block 111 is closed. When the playing of the roll is completed, the automatic rewinding of the music sheet takes place by the rewind hole 56 in the tracker-board being uncovered by registration therewith of the corresponding rewind perforation in the music sheet, whereupon the pneumatic 46 is collapsed, as previously described, which movement, through the medium of the coupling head 42, links 43, 44 and clutch lever 31, releases the clutch collar 28 from engagement with the take-up gear 23 and rocks the driving shaft 33 in the proper direction to withdraw its friction wheel 35 from the companion disk 27 and bring its friction wheel 34 into engagement with the companion disk 22 to unwind the music sheet on the music roll 11. Simultaneously with the collapsing of the pneumatic, suction acts on the diaphragm valve 95 to admit atmosphere to the inlet port 90 of the valve block 88 and cause the pouch valve 101 to close and cut off suction between 110 115 120 125

the suction bellows and the wind chest, so that the instrument remains silent during the rewind operation.

When the music sheet is completely un-

wound from the take-up roll 13, the pawl 103 drops by gravity into the locking recess 107 of said roll, thereby rocking the sleeve 105 in the proper direction to cause the pallet valve 109 of the valve block 111 to be opened, admitting atmosphere to its port 112 and cutting off suction to the pneumatic in the manner previously described, the spring 54 thereupon returning the pneumatic to its inflated position and restoring the parts controlled thereby to their normal playing position. Upon the inflation of the pneumatic, atmospheric pressure admitted to the port 69, passage 94, tube 93 and port 89 depresses the diaphragm valve 95, cutting off atmosphere to the air inlet port 90 and allowing the pouch valve 101 to open and establish communication between the suction bellows and wind chest to permit the instrument to play.

The manual act of stopping the playing of the instrument is accomplished by pulling the slide bar 49 outwardly, which movement shifts the clutch lever 31 in the proper direction to release the clutch collar 28 from the gear 23, the rock lever 52 being also actuated to move the spring valve 102 to its open position and admit atmosphere to its port 90 for the purpose of closing the pouch valve 101 and cutting off suction to the wind chest and the slide-valve 84 being likewise moved to its closed position to cut off suction to the pneumatic 46, in the manner previously described. This movement of the slide bar does not affect the position of the driving shaft 33 or the pneumatic owing to the pin and slot connection 47, 48 between the clutch actuating lever 31 and the link 43.

It will be understood that various changes in the construction and arrangement of the parts may obviously be made within the scope of the appended claims, and I therefore do not wish to be limited to the particular embodiment of the invention herein shown and described.

I claim as my invention:

1. In an instrument of the character described, the combination of take-up and music rolls, transmission mechanism including a driven member for each roll, one of said mechanisms including a roll-shaft having a gear loosely mounted thereon and a shaft for its driven member carrying a pinion in constant mesh with said gear, an oscillating driving shaft carrying driving elements arranged to alternately engage the driven members of said transmission mechanisms, respectively, a clutch for operatively connecting said loose gear with its roll-shaft, a shiftable lever for said clutch arranged on one side of the driving shaft, a pneumatic

disposed on the opposite side of said shaft, and means extending in opposite directions from the driving shaft for connecting it with said clutch lever and said pneumatic.

2. In an instrument of the character described, the combination of take-up and music rolls, transmission mechanism including a driven member for each roll, a shiftable driving shaft carrying driving elements arranged to alternately engage the driven members of said transmission mechanisms, respectively, a clutch for one of said transmission mechanisms, a shiftable lever for said clutch, a pneumatic, and links connecting the driving shaft with said clutch lever and said pneumatic, the connection of that link with the clutch lever being constructed to permit movement of the latter independently of the driving shaft and the pneumatic.

3. In an instrument of the character described, the combination of take-up and music rolls, a music-sheet, transmission mechanism including a driven member for each roll, one of said transmission mechanisms including a roll-shaft, a shaft for its driven member and a constantly meshing gear and pinion on said shafts, respectively, said gear being loose on the roll-shaft, a shiftable driving shaft carrying driving elements arranged to alternately engage the driven members of said transmission mechanisms, respectively, a clutch included in the transmission mechanism having said loose gear and mounted on the roll shaft thereof, means for maintaining said driving shaft and said clutch in their normally operative playing positions, and automatic means controlled by the music sheet and operatively connected to the driving shaft and the clutch for shifting these parts to their rewind positions when the playing of the music-sheet is completed.

4. In an instrument of the character described, the combination of take-up and music rolls, a music sheet transmission mechanism including a driven member for each roll, one of said transmission mechanisms including a roll-shaft, a shaft for its driven member and a constantly meshing gear and pinion on said shafts, respectively, said gear being loose on the roll-shaft, a shiftable driving shaft carrying driving elements arranged to alternately engage the driven members of said transmission mechanisms, respectively, for winding and rewinding the music sheet, a clutch included in the transmission mechanism having said loose gear and mounted on the roll shaft thereof, means for yieldingly maintaining said driving shaft and said clutch in their normally operative playing positions, and pneumatic means for shifting the driving shaft and the clutch to their rewind positions.

5. In an instrument of the character described, the combination of take-up and

music rolls, a music-sheet, transmission mechanism including a driven member for each roll, one of said transmission mechanisms including a roll-shaft, a shaft for its driven member and a constantly meshing gear and pinion on said shafts, respectively, said gear being loose on the roll-shaft, a shiftable driving shaft carrying driving elements arranged to alternately engage the driven members of said transmission mechanisms, respectively, for winding and rewinding the music sheet, a clutch included in the transmission mechanism having said loose gear and mounted on the roll shaft thereof, means for maintaining said driving shaft and said clutch in their normally operative playing positions, automatic means controlled by the music sheet and operatively connected to the driving shaft and the clutch for shifting these parts to their rewind positions when the playing of the music-sheet is completed, and means controlled by the take-up roll for releasing said automatic means to effect the return of said driving shaft and said clutch to their normal positions.

6. In an instrument of the character described, the combination of take-up and music rolls, a music sheet, transmission mechanism including a driven member for each roll, one of said transmission mechanisms including a roll-shaft, a shaft for its driven member and a constantly meshing gear and pinion on said shafts, respectively, said gear being loose on the roll-shaft, a shiftable driving shaft carrying driving elements arranged to alternately engage the driven members of said transmission mechanisms, respectively, for winding and rewinding the music sheet, a clutch included in the transmission mechanism having said loose gear and mounted on the roll shaft thereof, a pneumatic, means for connecting said pneumatic with said driving shaft and said clutch, means controlled by the music-sheet for causing the collapse of said pneumatic to shift said driving shaft and said clutch to their rewind positions, and means controlled by the take-up roll for causing the expansion of the pneumatic to shift said driving shaft and said clutch to their playing positions.

7. In an instrument of the character described, the combination of take-up and music rolls, transmission mechanism including a driven member for each roll, a shiftable driving shaft carrying driving elements arranged to alternately engage the driven members of said transmission mechanisms, respectively, a clutch for one of said transmission mechanisms, a rewind pneumatic, means for connecting said pneumatic with said driving shaft and said clutch, and valve mechanisms for controlling said rewind pneumatic, one of said valve mechanisms in-

cluding means for retaining the pneumatic in its collapsed position during the rewinding of the music sheet and the other valve mechanism including means for releasing the pneumatic to its expanded playing position upon the completion of the rewinding operation.

8. In an instrument of the character described, the combination of take-up and music rolls, a tracker board transmission mechanism including a driven member for each roll, a shiftable driving shaft carrying driving elements arranged to alternately engage the driven members of said transmission mechanisms, respectively, a clutch for one of said transmission mechanisms, a rewind pneumatic connected with the tracker-board of the instrument, means for connecting said pneumatic with said driving shaft and said clutch, valve mechanisms applied to said pneumatic for controlling the same, each of said valve mechanisms including a suction chamber, a valve chamber communicating by ports with said suction chamber and the atmosphere, a valve controlling said ports and a chamber communicating with the atmosphere and containing a diaphragm for actuating the valve, means for connecting the diaphragm chamber of one of said valve mechanisms with the tracker-board, and a valve-controlling the admission of atmosphere to the diaphragm chamber of the other valve mechanism, said controlling valve being actuated by the take-up roll.

9. In an instrument of the character described, the combination of take-up and music rolls, a tracker board transmission mechanism including a driven member for each roll, a shiftable driving shaft carrying driving elements arranged to alternately engage the driven members of said transmission mechanisms, respectively, a clutch for one of said transmission mechanisms, a rewind pneumatic connected with the tracker-board of the instrument, means for connecting said pneumatic with said driving shaft and said clutch, valve mechanisms applied to said pneumatic for controlling the same, each of said valve mechanisms including a suction chamber, a valve chamber communicating by ports with said suction chamber and the atmosphere, a valve controlling said ports and a chamber communicating with the atmosphere and containing a diaphragm for actuating the valve, an air conduit connecting the diaphragm chamber of one of said valve mechanisms with the tracker board, the pneumatic containing a valve passage communicating at one end with said conduit and at its other end with the valve chamber of the other valve-mechanism, and a valve for controlling the admission of atmosphere to the diaphragm chamber of the last-named valve-mechanism, said control-

ling valve being actuated by the take-up roll.

10. In an instrument of the character described, the combination of take-up and music rolls, a tracker board transmission mechanism including a driven member for each roll, a shiftable driving shaft carrying driving elements arranged to alternately engage the driven members of said transmission mechanisms, respectively, for winding

10 and rewinding the music sheet, a clutch for one of said transmission mechanisms, a rewind pneumatic connected with the tracker-board of the instrument, means for connecting said pneumatic with said driving shaft

15 and said clutch, valve mechanisms applied to said pneumatic for controlling the same, each of said valve mechanisms including a suction chamber, a valve chamber communicating by ports with said suction chamber

20 and the atmosphere, a valve controlling said ports and a chamber communicating with the atmosphere and containing a diaphragm for actuating the valve, means for connecting the diaphragm chamber of one of said

25 valve mechanisms with the tracker board, a valve block disposed adjacent to the take-up roll and containing an air inlet port communicating with the diaphragm chamber of the other valve mechanism, a valve applied

30 to said valve block for controlling the admission of atmosphere thereto, and a connection between said valve and the take-up roll for effecting the opening of the valve at the end of the rewind operation.

35 11. In an instrument of the character described, the combination of take-up and music rolls, driven members for said rolls, automatic driving mechanism including shiftable driving members movable in oppo-

40 site directions into and out of engagement with said driven members for alternately rotating said rolls in opposite directions, a clutch associated with one of said rolls, automatic shifting means for said driving mem-

45 bers and said clutch, and manual means independent of said automatic shifting means for moving said clutch relatively to said shifting members.

50 12. In an instrument of the character described, the combination of take-up and music rolls, driving and rewind wheels for alternately rotating said rolls, an oscillating shaft carrying wheels arranged to engage with said driving and rewind wheels, re- 55 spectively, a clutch associated with the take-up roll including a shiftable actuating member connected with said shaft, means for automatically oscillating said shaft and shifting said clutch member, and means for man- 60 ually actuating the clutch member independ- 65 ently of the oscillating shaft.

13. In an instrument of the character described, the combination of take-up and music rolls, driving and rewind wheels for

alternately rotating said rolls, an oscillating 65 shaft carrying wheels arranged to engage with said driving and rewind wheels, respec- 70 tively, a clutch associated with the take-up roll including a shiftable actuating member connected with said shaft, means for auto- 75 matically oscillating said shaft and shifting said clutch member, means for manually ac- tuating the clutch member independently of the oscillating shaft, including a shifting 75 bar, and a rock lever connected to said clutch actuating member and said bar.

14. In an instrument of the character de- 80 scribed, the combination of take-up and music-rolls, driving and rewind wheels for alternately rotating said rolls, an oscillating 85 shaft carrying wheels arranged to engage with said driving and rewind wheels, re- 90 spectively, a clutch associated with the take- up roll including a shiftable actuating mem- 95 ber, a link connecting said shaft with said member, a pin and slot connection between the latter and said link, a manually shift- 100 able bar, and a rock lever, one arm of said lever engaging said shiftable bar and its other arm engaging said pin.

15. In an instrument of the character de- 105 scribed, the combination of take-up and music rolls, a tracker board, transmission mechanism for each roll, a shiftable driv- 110 ing shaft carrying driving elements ar- 115 ranged to alternately engage the transmis- 120 sion mechanisms, respectively, a clutch for one of said transmission mechanisms, a shiftable lever for said clutch, a rewind 125 pneumatic connected with the tracker board of the instrument for effecting the automatic shifting of the driving shaft and the clutch lever to rewind and playing positions, re- 130 spectively, links connecting said driving shaft and said clutch lever with said pneu- 135 matic, and means for manually actuating said clutch lever independently of the driv- 140 ing shaft and the pneumatic.

16. In an instrument of the character de- 145 scribed, the combination of take-up and music rolls, a tracker board transmission mechanism including a driven member for each roll, a shiftable driving shaft carry- 150 ing driving elements arranged to alternate- 155 ly engage the driven members of said trans- 160 mission mechanisms, respectively, a clutch for one of said transmission mechanisms, a shiftable lever for said clutch, a rewind 165 pneumatic connected with the tracker board of the instrument for effecting the auto- 170 matic shifting of the driving shaft and the clutch lever to rewind and playing positions, re- 175 spectively, links connecting said driving shaft and said clutch lever with said pneu- 180 matic,—means for manually actuating said clutch lever independently of the driving shaft and the pneumatic, and separate means for yieldingly maintaining said pneumatic

together with said driving shaft and said clutch lever in their operative playing positions, respectively.

17. In an instrument of the character described, the combination of a wind chest, a suction bellows, take-up and music rolls, automatic driving mechanism including shiftable members for alternately rotating said rolls in opposite directions, a clutch associated with one of said rolls, a rewind pneumatic connected with the suction bellows of the instrument for automatically shifting said members and said clutch, a cut-off valve interposed between the suction bellows and the wind chest of the instrument, manual means independent of said automatic shifting means for moving said clutch relatively to said shiftable members, and a controlling valve for said cut-off valve actuated by said manually-shiftable means.

18. In an instrument of the character described, the combination of a wind chest, a suction bellows, take-up and music rolls, automatic driving mechanism including shiftable members for alternately rotating said rolls in opposite directions, a clutch associated with one of said rolls, a rewind pneumatic connected with the suction bellows of the instrument for automatically shifting said members and said clutch, a cut-off valve interposed between the suction bellows and the wind chest of the instrument, and an automatically-actuated valve connected to said rewind pneumatic and said cut-off valve for controlling the latter.

19. In an instrument of the character described, the combination of a wind chest, a suction bellows, take-up and music rolls, automatic driving mechanism including shiftable members for alternately rotating said rolls in opposite directions, a clutch associated with one of said rolls, a rewind pneumatic connected with the suction bellows of the instrument for automatically shifting said members and said clutch, a cut-off valve interposed between the suction bellows and the wind chest of the instrument, manual means independent of said automatic shifting means for moving said clutch relatively to said shiftable members, a valve box interposed between said pneumatic and said cut-off valve and having an air inlet, and a pair of valves applied to said valve box, one of said valves being automatically controlled and the other being operated by said manually-shiftable means.

20. In an instrument of the character described, the combination of a wind chest, a suction bellows, take-up and music rolls, driving and rewind wheels for alternately rotating said rolls, an oscillating shaft carrying wheels arranged to engage with said driving and rewind wheels, respectively, a clutch associated with the take-up roll including a shiftable actuating member con-

nected with said shaft, a cut-off valve interposed between the suction bellows and wind chest of the instrument, a valve block having an air inlet port communicating with said cut-off valve, a valve for said port, and means for manually actuating the clutch member and said valve including a shifting bar, and a rock lever operatively connected to said shifting bar and said clutch actuating member, the valve controlling said inlet port being arranged to be actuated by said rock lever.

21. In an instrument of the character described, the combination of a wind chest, a suction bellows, take-up and music rolls, driving and rewind wheels for alternately rotating said rolls, an oscillating shaft carrying wheels arranged to engage with said driving and rewind wheels, respectively, a clutch associated with the take-up roll including a shiftable actuating member connected with said shaft, a rewind pneumatic for automatically shifting said shaft and said clutch, a cut-off valve interposed between the suction bellows and the wind chest of the instrument, controlling valves interposed between said suction bellows and said pneumatic and between the latter and said cut-off valve, respectively, and means for manually actuating said clutch member and said controlling valves in unison.

22. In an instrument of the character described, the combination of a wind chest, a suction bellows, take-up and music rolls, driving and rewind wheels for alternately rotating said rolls, an oscillating shaft carrying wheels arranged to engage with said driving and rewind wheels, respectively, a clutch associated with the take-up roll and including a shiftable actuating member connected with said shaft, a rewind pneumatic connected with the suction bellows of the instrument for automatically shifting said shaft and said clutch-member, means for yieldingly maintaining said pneumatic, said shaft and said clutch member in their playing positions, duplex valve-mechanisms applied to the pneumatic for regulating the collapse and inflation thereof at the end of the playing and rewind operations, one of said duplex valves being connected with the tracker board of the instrument, an air inlet valve controlled by the take-up roll and connected with the other duplex valve, a cut-off valve interposed between the suction bellows and the wind chest, and an automatic valve connected with said pneumatic for controlling said cut-off valve.

23. In an instrument of the character described, the combination of a wind chest, a suction bellows, take-up and music rolls, driving and rewind wheels for alternately rotating said rolls, an oscillating shaft carrying wheels arranged to engage with said driving and rewind wheels, respec-

ly, a clutch associated with the take-up roll and including a shiftable actuating member connected with said shaft, a rewind pneumatic connected with the suction bellows of the instrument for automatically shifting said shaft and said clutch-member, means for yieldingly maintaining said pneumatic, said shaft and said clutch member in their playing positions, duplex valve-mechanisms applied to the pneumatic for regulating the collapse and inflation thereof at the end of the playing and rewind operations, one of said duplex valves being connected with the

tracker board of the instrument, an air inlet valve controlled by the take-up roll and connected with the other duplex valve, a cut-off valve interposed between the suction bellows and the wind chest, an automatic valve connected with said pneumatic for controlling said cut-off valve, means for manually shifting said clutch actuating member independently of said oscillating shaft, and a valve separate from said automatic valve for controlling said cut-off valve and operated by said manually shiftable means.

JOHN E. GRAF.
